UNITED STATES PATENT OFFICE.

FRED B. KING, OF TOLEDO, OHIO, ASSIGNOR TO THE WILLYS-OVERLAND COMPANY, OF TOLEDO, OHIO, A CORPORATION OF OHIO.

SPRING-SEAT CUSHION.

Application filed October 6, 1920. Serial No. 414,957.

To all whom it may concern:

Be it known that I, FRED B. KING, residing at Toledo, in the county of Lucas and State of Ohio, have invented certain new and useful Improvements in Spring-Seat Cushions, of which I declare the following to be a full, clear, and exact description.

This invention relates to improvements in spring seat cushions and more particularly to cushions for the seat backs of automobiles.

One of the objects of the invention is the provision, in a cushion having throughout most of its extent the ordinary type of coil springs, of a relatively soft edge portion obtained by the use of Marshall springs.

Another object of the invention is the provision of the Marshall springs in a convenient separate assembly or unit which may be readily attached to and united with the balance of the cushion.

A further object of the invention is the provision of a main or seat frame comprising cross slats so constructed at their intersections as to bring the principal portions of the slats into one plane while at the same time affecting as little as may be the strength of the entire structure.

Still another object is the provision of means for the attachment of the coil springs to the base frame which shall assist in holding the slats in proper position relative to each other.

Other objects, and objects relating to details of construction and economies of manufacture, will appear as I proceed with the description of that embodiment of the invention which, for the purposes of the present application, I have illustrated in the accompanying drawings, in which:

Figure I is a fragmental front elevation of a seat back cushion embodying my invention.

Figure II is a vertical section taken approximately on line II—II of Figure I, with a portion of the structure broken away.

Figure III is a fragmental detail elevation, or section on the line III—III of Figure II, showing an intersection of two slats.

Figure IV is a fragmental rear elevation of an upper corner of the seat cushion.

Figure V is a fragmental top plan view showing one corner of the Marshall spring unit.

Figure VI is a cross section on the line VI—VI of Figure IV, showing the manner in which one of two intersecting slats is offset in order to clear the other slat.

Like reference characters refer to similar parts throughout the views.

In the drawings, 10 refers to the relatively long horizontal slats, and 11 to the relatively short vertical slats of the main or base frame. At the points of intersection of the two series of slats, the vertical slats 11 are bent to provide forwardly extending offsets under which the long slats 10 extend with the result that the remaining portions of the two series of slats are flush with each other. The fact that the short slats 11 only contain bent portions, while the long slats 10 are unbent and continuous, is of advantage, as it is more important that the strength of the long slats be unimpaired by bends, than in the case of the short slats. The ends of the slats 10 and 11 are secured to a border wire 12 extending entirely around the frame, the fastening being effected preferably by the bending of the ends of the slats around the wire.

Each slat upon either side of its intersection with another slat has a struck up lip 13, the four lips at each intersection being adapted to engage the end coil of a coil spring 14 as shown particularly in Figures II and III.

The forward ends of the springs 14 are positioned with respect to each other by light wire, spiral springs 15, while the lower row and the side rows of springs 14 have their forward coils bound to a border wire 16 which surrounds three sides of the series of springs only, and has its ends terminating about half-way between the upper row of springs and the top part of the border wire 12. The means illustrated for attaching the springs 14 to the border wire 16 consist of metal clips 17.

Along the upper edge of the seat back I employ springs which are more easily flexed than the springs 14, which are of constant diameter and which are close together. These springs are encased in cloth.

A strip of cloth 18 is folded upon itself lengthwise and stitched transversely as at 19 so as to form pockets of proper size to receive the coil springs 20. Then the upper 5 edges of the cloth strip are stitched together as at 21. As shown in the drawing, I prefer to employ two such strips, but a greater or a lesser number might be used without departing from the spirit of my invention. 10 This is a well known form of spring structure which has come to be known as the Marshall spring, by which term it is referred to herein. For convenience in assembling the parts, I prefer to put these 15 Marshall springs into one assembly or unit. In forming this unit, a wire frame 22 of a length to fit between the side portions of the border frame 16 is employed and this frame is enclosed in a fabric casing 23 with 20 the one or more rows of springs 20, the casing forming a complete closure for the entire unit.

The Marshall spring assembly or unit is supported on the base frame above the top 25 row of springs 14 by wires 24 and 25 which are fastened in place in the frame by lips 26 struck up out of the slats 11 for that purpose. The wire 25 is also fastened at its ends to the border wire 12 as shown in 30 Figure IV. When the assembly is in place it is sewed by stitches, which include wherever possible, the lower loops of the springs 20, to the border frame 12 on the top and two sides, while at the bottom it is 35 sewed to the slats 11 and to the top row of springs 14 at the same time. The border wire 22 of the assembly is sewed not only to the casing 23 and individual springs 20, but also to the side members of border wire 16 and to the outer coils of the upper 40 row of springs 14.

The method of assembling my spring cushion will be obvious to those skilled in the art from a reading of the above description. In operation the action of the 45 lower portion of the cushion is similar to that of other cushions now in use, but the employment of the Marshall spring unit as a finish for the upper edge of the cushion 50 is novel so far as I am aware and has several advantages, some of which are that it makes the use of diagonal guy wires or 55 braces unnecessary, even for the lower portion of the cushion; that it forms a soft headrest; that its springs being of equal 60 diameter and close together present a flat upper edge surface; and that the relatively light wire in the springs enables the upholsterer to easily compress the upper outer corner of the finished cushion so as to round it off gradually and gracefully.

I am aware that my invention above described and illustrated in the accompanying drawings is susceptible of numerous 65 variations without departing from the spirit

thereof, and therefore I desire to claim my invention broadly as well as specifically, as indicated in the appended claims.

Having thus described my invention, what I claim as new and desire to secure 70 by Letters Patent, is:—

1. In combination, a base frame, a set of coil springs each having one end mounted on the base frame, means for holding positioned the opposite ends of the springs including a border wire extending around three sides of the set to which the adjacent springs are attached, an elongated cushion mounted upon the frame along that side of the said set of springs which is without a border wire, said cushion having a wire frame around the top thereof, and means for attaching said wire frame to the side elements of the border wire and to the upper ends of the adjacent springs. 75

2. In combination, a base frame, a set of coil springs each having one end mounted on the base frame, means for holding positioned the opposite ends of the springs including a border wire extending around three sides of the set to which the adjacent springs are attached, and an elongated cushion mounted upon the frame along that side of the said set of springs which is without a border wire, said cushion consisting of a Marshall spring assembly and having a wire frame around the top thereof, and means for attaching said wire frame to the side elements of the border wire and to the upper ends of the adjacent springs. 90

3. In combination, a frame, a set of coil springs each having one end mounted on the frame, means for holding positioned the opposite ends of the springs, said frame having mounted along one edge, a set of Marshall springs of relatively small wire, with their axes substantially parallel to the axes of the first named springs, said Marshall springs lying at all times wholly within the area bounded by said frame and constituting a part of said means for holding the free ends of the coil springs positioned. 105

4. In combination, a frame, a set of coil springs each having one end mounted on the frame, means for holding positioned the opposite ends of the springs, said set of springs terminating short of one edge of the frame, and an elongated cushion mounted upon the frame along said edge, and lying at all times wholly within the area bounded by said frame, said cushion consisting of a Marshall spring assembly 110 having a border wire at its top periphery to which the set of coil springs is attached. 120

5. In combination, a frame, a set of coil springs each having one end mounted on the frame, means for holding positioned the opposite ends of the springs comprising a border wire extending around three sides 125

thereof, said set of springs terminating short of the remaining edge of the frame, and an elongated cushion mounted upon the frame along said edge, said cushion consisting of a Marshall spring assembly having a wire frame around the top thereof, the bottom being tied to said first mentioned frame, the end portions of said wire frame being secured to the ends of said border wire.

6. In combination, a frame, a set of coil springs each having one end mounted on the frame, means for holding positioned the

opposite ends of the springs comprising a border wire extending around three sides thereof, said set of springs terminating short of the remaining edge of the frame, and an elongated cushion mounted upon the base of the frame along said edge, said cushion consisting of a Marshall spring assembly, and means securing together the adjacent outer edges of said set of coil springs and said Marshall spring assembly.

In testimony whereof, I affix my signature.

FRED B. KING.
